UNITED STATES PATENT OFFICE.

JAMES F. McELROY, OF ALBANY, NEW YORK.

TEMPERATURE-REGULATOR.

SPECIFICATION forming part of Letters Patent No. 471,523, dated March 22, 1892.

Application filed February 11, 1891. Serial No. 381,103. (No model.)

To all whom it may concern:

Be it known that I, JAMES F. McELROY, a citizen of the United States, residing at Albany, in the county of Albany and State of New York, have invented certain new and useful Improvements in Temperature-Regulators, of which the following is a specification, reference being had therein to the accompanying drawings.

10 This invention relates to new and useful improvements in temperature-regulators; and the invention consists in the peculiar construction of a temperature-regulator whereby it may be adjusted to open or close a valve or 15 damper at varying temperatures, and, further, in the peculiar construction of the connecting mechanism between the temperature-regulator and the valve or damper, and, further, in the peculiar construction, arrangement, and 20 combination of the various parts, all as more fully hereinafter described.

In the drawings, Figure 1 is a front elevation of my improved damper-regulator, showing the connections to the valve and the valve 25 and one of the elbows in section. Fig. 2 is a vertical central section through the temperature-regulator, partly in elevation. Fig. 3 is a vertical section through the elbow.

A is the frame of the temperature-regulator, which is centrally provided with a screw-threaded aperture, in which a block or plug B, having a suitable screw-threaded shank, engages. To this block is secured an expansion-chamber C, preferably formed of two circular disks secured together at their edges. This expansion-chamber is provided on its front face centrally with a bearing-plate D, which bears against the lever E, pivoted at the lower end of the frame and extending to 40 near the top thereof, where it engages with one end of a bell-crank lever F, pivoted in the frame, the other end extending to the rear of the frame, where it is connected with a vertical actuating-rod G. This rod is screw-threaded and is provided with lock-nuts H, adapted to strike against a rod or flange I to limit the movement of the rod, so as to prevent damage to the valve or valve-seat. This rod connects at its lower end with the upper 45 end of the rod J, which is suitably guided through the frame of the machine.

K are lock-nuts on the rod J, against which

the spring L bears to hold the valve normally in its open position.

The frame A is provided at its lower edge 55 with a screw-threaded socket M, into which a pipe N engages, this pipe forming a rigid frame to connect the valve-casing of the steam-supply valve with the frame of the temperature-regulator, so that the valve-casing 60 and temperature-regulator frame may always remain at a fixed distance apart. It frequently happens in such constructions that the temperature-regulator cannot be placed directly over the valve, in which case it becomes necessary to use an elbow O in the pipe 65 N. This elbow is of such shape as to allow of a bell-crank lever P being pivoted therein upon a pin Q, which I preferably cast integral with the elbow-casing. One arm of the 70 bell-crank extends in line with the vertical pipe N and the other arm extends in line with the horizontal section R, which extends a suitable distance to a point over the valve-casing S, another elbow with a suitable bell-crank lever being placed over the valve to give a vertical movement to the valve-stem, as plainly shown in the drawings. One side of the elbow is open, and this is adapted to be closed by means of a face-plate S', which 75 has a lug T against the end of the pin Q to hold the bell-crank lever upon its pivot. It is also provided with a suitable aperture to receive a screw T', entering a hollow post U to secure the cap in position. By means of 80 this construction I am enabled to construct a rigid frame from the frame of the temperature-regulator to the valve-casing, making all necessary bends.

As the pins upon the ends of the bell-crank 90 lever loosely engage in the ends of the rods, being held from displacement by the plate S', it is evident that if that plate is taken out the bell-crank lever is detached by simply withdrawing it from its pivot-post and withdrawing the pins from the ends of the connecting-rods.

In order to vary the operation of my thermostat, I connect to the block B a suitable hand-lever U', by means of which the block, 100 together with the expansion-chamber, may be turned. The turning of this block by means of the screw-threaded shank engaging in the screw-threaded aperture carries the expansion-chamber with it.

sion-chamber toward or from the lever E, requiring a greater or less expansion in the expansion-chamber to effect said lever and the valve.

5 I have found that with a comparatively small movement of the lever U I could vary the point at which the valve would be closed from eight to ten degrees.

- What I claim as my invention is—
- 10 1. The combination, with a thermostat, its frame, and a valve controlled thereby, of a rigid frame connecting the valve-casing and thermostat-frame and comprising an elbow or bend, a bell-crank lever pivoted in the elbow, and an actuating-rod connected thereto and extending on both sides thereof, substantially as described.
  - 15 2. In a temperature-regulator, the combination, with the frame, of a thermostat consisting of a cell containing an expansible medium, a central screw-threaded shank secured to said cell, and a lever for rotating said cell and adjusting it to or from the actuating medium, substantially as described.
  - 20 25 3. The combination, with a temperature-regulator and a rigid tubular frame connecting the frame of the regulator with the valve-

casing, of an elbow O, having a pin cast integral therewith, a bell-crank lever having a socket formed thereon adapted to fit upon said pin, and bearings at the end of said lever to connect with the actuating-rods, substantially as described.

4. In a device of the kind described, the combination, with the tubular frame, of the elbow O, having the pin Q cast integral therewith, the bell-crank lever P, and the face-plate S', forming a cap for the pivot-pin Q, the parts being arranged to operate substantially as and for the purpose described.

5. In a temperature-regulator, the combination, with a supporting-frame and valve-actuating mechanism on the frame, of a thermic cell arranged between the mechanism and the frame, a supporting projection on the cell, and an adjustable connection between the projection and frame, substantially as described.

In testimony whereof I affix my signature in presence of two witnesses.

JAMES F. McELROY.
